UNITED STATES PATENT OFFICE

HOWARD W. JELLIFFE, OF CLEVELAND, OHIO

ELECTRICAL HEATER FOR ENGINE-JACKET SYSTEMS

Application filed March 16, 1927. Serial No. 175,777.

This invention relates to electrical heaters for engine jacket systems, and more especially to heaters for systems connecting the jackets of auto engines with the radiators, more particularly for internal combustion engines as auto motors. It is my purpose to provide a heating unit that is readily removable from the mounting device that is incorporated in the circulating systems usually connecting the radiator with the engine, as the jacket of the latter.

It is an object of my invention to provide a **T** whose vertical pipe is ordinarily secured to the longitudinal tube and permitting circulation of liquid from the said system up into the vertical portion where a heating unit is mounted and provided with connections with suitable electric current, though detachably, whereby the cooler system of the engine may be made use of for maintaining heat in such system while the vehicle is stationary and the engine is not running.

It is a further object of my improvement to construct such heating unit for attachment with the cooler system of an automobile whereby the unit will be mounted to be readily connected detachably with the various tubes of the system, so that the unit may not only be conveniently positioned as desired, but may also be quickly replaced when repairs are necessary.

In the drawings:—

Figure 1 is a side elevation of my improved heating unit for cooling systems shown connected with the same;

Figure 2 is a side elevation of the same but turned at an angle of 90° to the former;

Figure 3 is a central, vertical section taken on the line 3—3 of Fig. 1;

Figure 4 is a side elevation of the heating unit only as removed from the socket, and a portion broken away;

Figure 5 is a cross section taken on the line 5—5 of Fig. 2;

Figure 6 is an elevation of a modified form of unit to be connected with the cooling system in the same manner as the first form;

Figure 7 is a central, vertical section of the latter form taken on the line 7—7 of Fig. 6;

Figure 8 is a cross section taken on the line 8—8 of Fig. 6, and

Figure 9 is an elevation of a detail.

Like parts are designated by similar reference characters throughout the description of the various views.

It is to be noted that I have provided an upright and elongated cup member 5 made of metal, usually but not essentially of brass, having a closed end at the bottom and an enlarged open end, the latter being provided with stepped enlargements forming thereby, shoulders, the upper one being designated by numeral 6 upon which the weight of the cup 5 will ordinarily rest as it bears upon the outer structure later to be described more in detail. This cup structure is designed to be readily removed from the said outer mechanism, as will be later explained.

The structure to be directly associated with the cooler system of the auto, comprises a tubular piece 7 whose ends extend in the direction of the pipes of the system, and will enter the pipes and be detachably secured therein by the application of screw bands 8, about the pipes 10 usually of some caoutchouc composition, and tightened thereover to hold the piece 7 in the circuit. An opening 29 is made in a segment of the said piece 7, to permit free circulation between the latter and the space 9 about the said member 5, whereby heat in the latter will be communicated to the contents of the pipes 10 forming the circulatory system. Of course, the said opening 29 need not be perfectly segmental, since the connection, later to be explained, between the main piece 7 and the vertical tube means to be attached thereto, may be somewhat outside the outline of such opening, at least, it is not essential that such attachment and said opening shall be uniform in size and shape.

A vertical tube member 11 is designed to enclose the lower end of the piece or member 5, though somewhat spaced therefrom, as shown in Fig. 3, and will usually be of a radial size approximately that of the piece 7. The tube 11 will ordinarily be of a standard radial size, and its lower opening shaped to fit over varying sizes of the pieces 7 which will fit the given hose or other pipes 10. To

accomplish this, the aperture 29 will be made of a standard size which will be that used when attaching to the smaller sizes of pieces 7, and the lower end of the member 11 will 5 then be cut concave in cross section to contact the surface of the piece 7, as shown in Fig. 3. It is my intention in this construction to extend the upper end of the part 11 less than one half the length of the member 5, another 10 tubular member 13 being applied over the upper end of the member 5 though spaced thereabout and spaced from the edge of part 11, a section 14 of hose or similar material enclosing the separated ends of the parts 11 and 15 13 to connect watertight these parts by the provision of a pair of clamps 15 tightened about the ends of section 14 to bind them against parts 11 and 13.

The member 5 contains therein the heating 20 element 16 having the usual connections 17 to which a suitable plug, or other means for leading wires from a suitable source of electric energy, may be detachably connected. No claim is made to this particular feature. 25 A central core 18 is suspended from an upper cap 19 of similar dielectric material which is shaped to fit within the member 5 but having a peripheral flange 20 extending out over the enlarged cylindrical portion 21 of 30 member 5, as shown in Fig. 3. From one said connection 17 a conductor 22 leads down through the center of the core 18, and at the bottom of the core is directly connected with the conductor 25 leading from the other connection 17 and spirally wound about the core 18, and insulated by a suitable dielectric substance 24, the said spirals of the element 25 being closely positioned adjacent the interior surface of member 5, as illustrated.

40 In Figs. 6, 7 and 8, I have shown a second form of mounting the heating unit in the cooling system, in which second form of heater, I provide cylindrical members 31 and 33 spaced about the member 35, but not wholly 45 separated, the part 33 being connected directly, though detachably to the cylindrical member 31. The band 26 binds the parts 31 and 33 together in this second form. These parts 31 and 33 are sufficiently elongated to 50 telescope for a certain distance, as at 23, so that but one encircling band 26 will be required to bind the ends of the parts 31 and 33 together. The connection of these parts will 55 be detachable, however, so that by loosening the band 26, the parts 31 and 33 may readily be disengaged for the removal of the member 35 and contents therefrom for any purpose.

In the second form it has been found advantageous to split the lower end of the upper 60 or outer part 33 at one or more points 27, making easier the insertion of the lower tube part 31 into the lower end of the upper part 33 before tightening the encircling band 26 about the telescoped ends. In this form, the 65 receptacle member 35 is provided with an

upper flange 30 resting upon the upper edge of the tube member 33 and is fixed thereto by soldering or welding at 34, as shown in Fig. 7. The member 35 receives detachably the heating element 16 or another that may be desired to use and is of the proper shape and size, the form of heater unit, including the cap member 19 and the suitable connector clips 17, being determined by local conditions largely. It is however, to be understood that 70 the unit 16 is to be removable from the receptacle member 5, in the one case, and from the member 35 in the other, but the parts 33 and 35 are fixedly secured together at 34; and the tube 13 of the first form fixed to the 80 shoulder 6 of the member 5 by welding or soldering at 4, as shown in Fig. 3.

In the second form shown in Figs. 6, 7 and 8, the encircling band 28 is just outside of the tube members 33 and flange 30, and is 85 secured to both. Within this socket at the upper end of the heater, the cap 19 may rest with the weight of the suspended element 16 borne thereby. By this arrangement, lifting the upper tube member 33 from the tube 31, the band 26 having been removed, will leave upon the piece 36 only the tube 31, and the metal band 26, if the latter is not detached from the tube 33 by loosening, may drop upon the piece 36 or be carried about the lower end 90 of the tube 33. In either case, the upper section 33, when removed from the lower section 31, takes with it the heater unit 16 in its case 35 connected to the upper tube 33 at the welding point 34.

In the first form, the upper tube 13 may be removed from the lower tube 11 by loosening the lower band 15, when the hose cylinder 14 will be carried by the upper tube 13 together with the enclosed heater unit 16 and the cup member 5 which latter is welded or soldered securely to the tube member 13 at the point 4, as shown in Fig. 3.

Operation.—The main section—7 of the first form and part 36 of the form in Fig. 7, 110 each forms together with the lower tube member 11 or 31, a T which is readily insertible in the cooler system of an auto, the size of the base tube, 7 or 36, being variable as may be desired, the part 36 of the second form being 115 shown as relatively larger than the part 7 of the first form. In either form, however, ends of the tubes—usually hose—of the said system are telescoped over the ends of the base tube, as above stated, and ordinarily clamps 8 120 tightened about the hose ends, as shown in Figs. 1 and 5.

In the first form of the T, the lower tube 11 is soldered or welded to the base 7 at the segmental edge 12 and about the opening in the base, while in the second form the tube 31 of the T is soldered or welded to the base 36 on the edge 32. In either case, the heater unit 16 and its supports are detachably connected with the lower tubular member, 11 130

or 31. A conspicuous arrangement of the improved structure is the ready attachment to the main and lower member or **T**, of the heater unit, without any special provision for mounting of the heater in the system—the heater may be connected therein or removed therefrom. Only the open tubular element 11 or 31, is bent out of the line of the system pipes, even when the heater unit and carriers for it are wholly removed. In such case the tube, 11 or 31, may be covered as desired when the heater unit is temporarily removed.

In either form of the heater case, an open space 9 is furnished between the inner casing 5 carrying therein the unit 16, and the outer casing 14 connected by the tubes 11 and 13 in the first form; and between the casing 35 and tubes 31 and 33 of the other form of construction. Heat generated, therefore, in the heater element 16 within the cup member 5 or 35, will be transmitted to the fluid in the space 9, and thereby to the fluid in the base member 7 or 36 of the **T**, and thence to the tubes of the system to be heated from said base member.

It is claimed as a special advantage of the plan shown for mounting the heater upon the **T**, that no unusual means for supporting the heater need be provided, since the weight 30 of the heater, including parts 16 and 18, rest above the **T**, and the connection of the heater with the lower cylinder 31 or 11 of the **T** does not require relative rotation of any of the parts, an advantage which will be readily 35 evident. For this reason none of these telescoping parts are threaded together. It will also be seen that no disadvantageous position of the heater will be necessary or desirable to attain the heating function when the heater is detachably connected by the clamps 15 or 26 with the lower member 11 or 31. The **T** may therefore be constructed with a standard tube 11 or 31 of a size to readily receive the unit 16 in the member 5 or 35, while the 40 base tube of the **T** may be of different sizes to fit the pipes of the circulatory system, as above explained. My construction permits the use of a heater with its cup member of desired length, and provides mounting of the 45 same in connection with the circulatory system without using a cross member of the **T** of a length equal to even approximately that of the heater. Indeed, in both forms the integral parts 11 and 31, of the **T**, are less than one half the length of the heater members 5 or 35. This has a great practical advantage, 50 since when the band 15 or 26 is removed, the heater parts with their mountings, including the members 14 or 33, only the members 11 or 60 31 will remain integral with the **T**. It is therefore desirable to shorten these cross members 11 or 31 as much as possible. When the heater is removed, it is only necessary to provide a suitable cap or cover for these cross members which are not extending detriment-

tally to the use of the system, when the heater is removed.

While I have referred to the system to be heated as the cooler system of auto engines, which may be the engine jacket system, I am not to be understood as limited to such particular circulatory system, but I propose to use the heater unit for heating various pipe systems other than the cooler systems of autos.

Having now described my invention and the manner of its application, what I claim and desire to secure by Letters Patent of the United States, is—

1. An electrical heater for insertion in the cooling system of an internal combustion engine comprising, a **T**-member whose alined ends are adapted for connection in such system and whose cross tube is open and relatively short, a cylindrical element mounted in axial alinement with the said cross tube and connected therewith by telescopic, threadless connection and extending upwardly therefrom, an elongated cup member of smaller radius than said cross tube but of a length greater than the combined lengths of the cylindrical element and the cross tube, having an enlarged upper end forming a shoulder welded upon the edge of the said cylindrical element, a clamp engaging the said connection of the said alined cylindrical element and tube externally thereby forming an imperforate inner space between the alined tubes and the said cup member, and an electrical heater unit removably positioned within said cup member.

2. An electrical heater for insertion in the cooling system of an engine comprising, a **T**-member whose alined ends are adapted for connection in such system and having a relatively short cross tube, a tubular element mounted detachably in axial alinement with the said cross tube, the intermediate ends of the alined tubes being threadless and adapted to be telescoped in operative position, clamp means for binding the said telescoped ends together detachably, an elongated cup member of a length equal to substantially the combined length of the tubular element and cross tube and having an enlarged upper end forming a shoulder secured upon the edge of the detachable tubular member by welding with the cup member spaced interiorly from the telescoped members, whereby the removal of the upper telescoped member will carry with it the cup member and its contents, an electrical heater unit removably seated within said cup member, by threadless connection therewith and connections from said heater unit for attachment to a source of electrical energy.

In witness whereof I have hereunto set my hand this 14th day of February, 1927.

HOWARD W. JELLIFFE.
